UNITED STATES PATENT OFFICE.

SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

LOCK.

1,403,127.

Specification of Letters Patent. Patented Jan. 10, 1922.

Application filed July 21, 1919. Serial No. 312,251.

To all whom it may concern:

Be it known that I, SAMUEL SEGAL, a citizen of the United States, and a resident of New York, in the county of New York and 5 State of New York, have invented certain new and useful Improvements in Locks, of which the following is a specification.

My invention has for its object the production of a lock of extreme simplicity of 10 construction and of positiveness of operation which shall be adapted to effectively perform its locking function and which shall also be adapted to be applied to doors either of the swinging or sliding type. 15 Other and further objects of the invention will appear from the accompanying description, the invention consisting in the novel parts and combinations of parts hereinafter more particularly described and then 20 specified in the claims.

In the accompanying drawing showing a practical embodiment of the invention:

Fig. 1 is a front elevation of my improved lock as applied to a door.

Fig. 2 is a side elevation of the lock and a cross-section through the door.

Fig. 3 is a vertical section on the line 3—3 of Fig. 2.

Fig. 4 is a horizontal section on the line 30 4—4 of Fig. 3.

Fig. 5 is a perspective view of my improved keeper.

Referring in detail to the several figures of the drawing:

1 indicates a door, either of the swinging or sliding type and 2 the door jamb. The casing 3 containing the locking mechanism is provided with a removable cover 4 and is fastened to the inner face of the door in 5 any desired manner, preferably by screws as shown. The end of the casing 3 extends inwardly over the space between the door and door jamb a distance sufficient to prevent interference or tampering with the 10 locking mechanism within the casing by the insertion of a jimmy or other tool within the space and which, on account of the cut-away portion 5 with which an end of the casing is provided, might ordinarily be possible if the casing were not so positioned. When the casing is fastened to the door in the position shown, a tool inserted within the space between the door and door jamb would merely strike the casing itself and

would not interfere with the mechanism 55 therein.

6, 7 indicate opposed locking bolts pivotally mounted at their ends, as at 6' 7' within the casing 3. Said locking bolts, adjacent their pivoted ends, are thickened or 60 enlarged as indicated at 8, 9 and their opposite ends terminate in hooks 10, 11 having curved edges as illustrated. Said locking bolts 6, 7 are connected together by a spring 12 the action of which tends to draw them, 65 or cause them to swing, towards each other on their pivots into engagement with a stop 13 which is fastened to or made a part of the inner wall of the casing. Said stop 13 is provided with squared projecting fingers 70 14, 14' fitting within the squared indentations or notches 15, 15' with which the locking bolts are provided. The purpose of providing these projecting fingers and indentations engaging or interfitting with 75 each other when the locking bolts are in normal or locked position, or that position clearly shown in Fig. 3, is to prevent the pivots 6' 7' being subjected to too much strain in the event that the casing has not 80 been properly positioned on the door and a tool has been inserted in the space between the door and door jamb and in the cut-away portion 5 and lateral pressure applied to the locking bolts to displace them in an endeavor 85 to break the lock.

My improved keeper which is adapted to be engaged by the hooked ends 10, 11 of the locking bolts comprises an angle piece 16 which is secured to the corner of the door 90 jamb by suitable screws or otherwise and preferably countersunk therein and which forms a base plate for the keeper, an upright member 17 which in the preferred form of the invention is substantially parallel to one side or face of said base plate and connected to said side by a transverse member 18, said upright or parallel member being provided with inclined outer surfaces or sides 17' extending in opposite directions and flanges 100 19 extending upwardly and downwardly from the transverse member 18. All of said parts are preferably integral and they cooperate together to form upper and lower pockets, as is clear from an inspection of 105 Fig. 5, for the reception of the hooked ends 10 and 11 of the locking bolts 6 and 7 which interlock therewith.

20 indicates the face plate and 21 the tumbler barrel of a cylinder lock of the well-known type which is anchored, as is the usual case, to the inner wall of the casing by suitable bolts 22. Extending within the casing from the tumbler barrel 21 and through the cam 23, which it is adapted to actuate, is the operating spindle 24. Said operating spindle also extends into the hollow latch 10 knob 25 which is mounted in the cover 4 of the casing and through the cam 26 which it is adapted to actuate and which is carried within the casing by the shank of the knob on which it is mounted. As the cams 23 and 26 15 engage the thickened parts of the locking bolts 6 and 7, these bolts may be operated by means of a key inserted in the face plate 20 of the cylinder lock and turned therein or by turning the latch knob 25 on the inside 20 of the door, whereby the cams 23 and 26 are actuated by means of the operating spindle 24 and the locking bolts 6 and 7 are forced by the cams to swing on their pivots away from each other against the action of the 25 spring 12 thereby lifting their hooked ends 10, 11 out of engagement with the keeper. The locking bolts may be retained or held in unlocked position by a turning of the cams 23 and 26 to a position whereby the highest 30 points of their cam surfaces are in vertical alignment or to a position at right angles to that shown in Fig. 3.

When the door is open and the locking bolts are in normal position or that position 35 shown in Fig. 3, the door may be automatically locked by merely closing the same without it first being necessary to manually spread the bolts or move them away from each other. In the case of a swinging door, 40 upon closing the same, the hooked ends 10 and 11 of the locking bolts strike forwardly against the inclined surfaces 17' of the vertically extending member 17 of the keeper along which they ride, against the action of 45 the spring 12, until they clear the top edges of said inclined surfaces, when they will be forced automatically by the action of the spring into the pockets of the keeper herein-before described. In the case of a sliding door, upon closing the same the curved edges 50 of the hooked ends 10 and 11 of the locking bolts strike laterally against the flanges 19 of the transverse member 18 of the keeper which forces the locking bolts apart until the 55 hooked ends fall into the pockets of the keeper in an obvious manner.

When the hooked ends of the locking bolts are within and are interlocked with said pockets they fit snugly intermediate the base 60 plate of the keeper and the upright member 17 thereof and a side of each of said hooked ends engages or is immediately adjacent to the flanges 19 of the keeper. Therefore, as is obvious, when said hooked ends are interlocked with said pockets a movement of the

locking bolts in any direction is impossible except a movement on their pivots which may only be effected by means of a key inserted in the face plate 20 or by turning the latch knob 25.

70

What I claim as my invention is:—

1. In a lock, the combination with a keeper comprising a base plate, an upright member, a transverse member joining said upright member with the base plate and flanges extending upwardly and downwardly from said transverse member to form pockets, of a pair of pivoted locking bolts having hooked ends adapted to interlock with the pockets formed in said keeper whereby any movement of said locking bolts except a pivotal one is prevented.

2. In a lock, the combination with a keeper, of a casing, a pair of locking bolts pivoted within said casing and provided with squared indentations therein and with hooked ends, a stop within said casing and between said locking bolts, squared fingers on said stop adapted to engage and to interfit with said indentations to prevent a lateral displacement of said locking bolts and a spring connecting said locking bolts and tending by its action to force them to engage said stop, said hooked ends of said locking bolts being adapted to automatically interlock with said keeper upon engagement therewith.

3. In a lock, the combination with a keeper comprising a base plate, an upright member, a transverse member joining said upright member with the base plate and flanges extending upwardly and downwardly from said transverse member to form pockets, of a pair of separated pivoted locking bolts having means tending to draw them together, said locking bolts being adapted to interlock with the pockets formed in said keeper, whereby any movement of said locking bolts except a pivotal one is prevented.

4. In a lock, the combination with a keeper comprising a base plate, an upright member, a transverse member joining said upright member with the base plate and flanges extending upwardly and downwardly from said transverse member to form pockets, of a pair of pivoted locking bolts having hooked ends, a stop between said locking bolts and a spring connecting the same and tending by its action to force them to engage said stop, said hooked ends of said locking bolts being adapted to automatically interlock with the pockets of the said keeper upon engagement therewith whereby any movement of said locking bolts except a pivotal one is prevented.

5. In a lock, the combination with a keeper comprising a base plate, an upright member provided with inclined sides, a

transverse member joining said upright member with said base plate and flanges extending upwardly and downwardly from said transverse member to form pockets, of
5 a pair of pivoted locking bolts having hooked ends with curved edges, the hooked ends of said locking bolts being adapted to automatically interlock with the pockets of said keeper upon engagement of said ends
10 with the inclined sides or flanges thereof

whereby any movement of said locking bolts except a pivotal one is prevented.

Signed at New York, in the county of New York and State of New York, this 19th day of July, A. D. 1919.

SAMUEL SEGAL.
